UNITED STATES PATENT OFFICE.

FRANCIS H. RICHARDS, OF HARTFORD, CONNECTICUT, ASSIGNOR TO THE STANLEY RULE & LEVEL COMPANY, OF NEW BRITAIN, CONNECTICUT, A CORPORATION OF CONNECTICUT.

LOCKING MECHANISM.

SPECIFICATION forming part of Letters Patent No. 766,791, dated August 2, 1904.

Application filed October 2, 1903. Serial No. 175,421. (No model.)

To all whom it may concern:

Be it known that I, FRANCIS H. RICHARDS, a citizen of the United States, residing in Hartford, in the county of Hartford and State of Connecticut, have invented certain new and useful Improvements in Locking Mechanism, of which the following is a specification.

This invention relates to and has for an object to provide an improved and efficient locking mechanism.

In many structures certain of the working parts are carried by a framework pivoted to the main frame of the device and wherein such working parts must be held at various positions relative to the main framing while they are performing their work. In wood-sawing machines, particularly miter-boxes, a main framing will be provided which will have faces to position the work, and the saw will be controlled by guides carried upon a beam accurately pivoted to the main frame, and which beam will be halted at the various positions desired to produce by the saw-cut various angles or bevels upon the work which is being sawed.

In one form of my invention the beam will be provided with a clamp so organized that spring-pressure will cause it to clamp the beam onto or against the frame and hold the saw-guides in position while the saw is doing its work, and the spring which actuates such clamp will be under the control of the operator in such a manner that he may while swinging the beam remove either the entire spring-pressure from the clamp or diminish its action upon the clamp to a greater or less degree, as he may desire.

When it is desired to swing the beam-arm from side to side of the frame, the clamp may have the entire spring-pressure removed from it, and upon the near approach to the desired position the spring may be released somewhat, so that its control may be exerted upon the clamp and felt by the beam to steady the saw, so that there will be no reciprocation of the parts when it is being brought to the exact position. Thus by letting the clamp

initially or tentatively become active it will not throw the parts out of position upon being released to the full extent. It will not have the same effect as if the parts were positioned and the clamp permitted to spring violently into action.

In wood-sawing machines, such as miter-boxes, there are certain angles generally used in construction, such as the miter and some of its regular divisions, and for the purpose of producing such standard bevels a precisionizing device in the nature of an additional fastening may be provided—such, for instance, as a bolt or index-pin to lock the parts at the adjusted position in addition to the grip of the clamp. Such bolt or index-pin may be regarded as a precisionizing element, first precisionizing and afterward coöoperating with the clamp to lock the saw in position. The bolt may be so located that it will be controlled by the same lever or actuator which controls the clamp.

In some structures the clamp may be controlled by a rock-shaft having fast upon it a rocker-arm, and upon the rocker-arm the force of a spring or springs will be exerted, so that upon moving the rocker-arm the spring force upon the clamp will be modified or abated, as may be desired, and the index-pin may be under the control of such rocker-arm and so positioned that it will not be acted upon until the force of the spring upon the clamp has been materially modified. When the index-pin has been completely withdrawn from its locking position, the force of the spring will be entirely removed from the clamp, so that the parts may move freely and the beam be brought to its desired position. Upon permitting slight movement of the rocker-arm the clamp will become slightly active and the index-pin released to the action of its individual spring or other throwing device, whereby the clamp will control the beam to a certain extent, and in its passage in either direction, particularly toward the position at which it is to be set, will cause the beam to move slowly, and upon the arrival of the index-pin

at its locking-cavity it will automatically assume its locking position, and thus precisionize and halt the beam at the exact position.

The index-pin and its actuator may be so organized that it will be controlled at the last period of the movement of the rocker-arm and the clamp be influenced by any movement thereof. The movement in one direction of the rocker-arm takes the pressure off the clamping-bolt and diminishes the gripping action or power, which action is diminished up to the point where the index-pin is entirely withdrawn from its bolt-hole, and such pin is held from the bolt-holes, or rather is held in its withdrawn position, by riding upon a face of the frame between the bolt-holes, so that it is free to find entrance into the bolt-hole upon its arrival thereat. Thus it will be seen that the bolt and clamp may be held entirely inactive or the clamp may be partially released to the action of the spring controlling it and the bolt entirely released to the control of its spring to freely enter the bolt-hole upon its coming into position so to do.

In some instances it will be desired in sawing to follow a line upon the work or else by means of some instrument to use the saw at some position other than one of the set angles for which the machine has been constructed, in which case the clamp will be sufficient to hold the beam at the point where it may be thus halted without the intervention of the index-pin. The presence of the pin in the organization being largely to locate the parts at the various positions, so that the workman may see by a scale to what point he is adjusting the instrument and receive an indication that the saw-carrying member has reached the desired position by the index-pin seating in the hole for such position, and the saw there adjusted will be precisionized without recourse to any measurements on his part. The saw may by this means be securely held between operations at the angle at which it is set; but when the workman does have to resort to measurements the need then for the index-pin is absent, and the clamp will not require any additional or coöperative securing means.

In the drawings accompanying and forming part of this specification a form of my invention is illustrated applied to a miter-box, wherein—

Figure 1 is a plan view showing a miter-box equipped therewith. Fig. 2 is a front view of the same. Fig. 3 is a central cross-section. Fig. 4 is an enlarged side view of one end of the beam, showing the clamping and locking mechanism. Fig. 5 is a plan view thereof. Fig. 6 is a side view of a similar portion partially in central section. Fig. 7 is a perspective of an index-pin actuator. Fig. 8 is a form of index-pin. Fig. 9 is a perspective of

a form of clamping-block, and Fig. 10 is a perspective of a form of rock-shaft for actuating the clamping-block.

The main frame of the machine or miter-box herein illustrated is shown as comprising a bed-plate 8, supported by suitable feet 9 and having upon the bed 8 a board flooring 10 to protect the saw-teeth from contacting with the metal of the framing. A back 11 is shown as projecting rigidly from the bed-framing 8 and having a flat face 12 for positioning the back of the work. A saw-opening 13 divides the back and is provided with beveled sides 14 to accommodate the saw in its various positions. A hub 15 is carried by the lower part of the frame and on which hub a beam-arm 16 is pivoted by means of a bushing 17, which passes through the beam and has a head or bead 18, which rests upon a portion 19 on the beam, the diaphragm being surrounded by a ring or flange 20. The body of the bushing almost reaches a face 21 inside of the hub and which bushing has the line of its axis in the plane of the face 12 of the back, the clearance being designated by 22. The bushing is made to fit snugly within the opening in the portion 19 and to have a working fit therewith and is held in position on the frame and beam by means of a set or binding screw 23, which has an easy working fit with the bushing and enters a tapped hole in the frame and may be jammed down hard with impunity without interference with the movement of the joint. A hub 24 on the beam engages the face of the hub 15. The beam has an end protruding beyond the back plate and carrying a hub 25, affording a socket for a saw-guide, and the beam also protrudes beyond the frame at the front, affording a handle 26, and there carries two hubs 27 28, affording sockets for a saw-guide, whereby it may be exchanged from one to the other socket.

The shifting of the saw-guides is rendered possible by the stay-rod 100, passing through a head or yoke 102, having a set-screw, which may be a thumb-screw 101, to clamp it in position, taking into a portion of the saw-guide. The bar 100 will of course steady the guides, and upon the stepping of one of the guides from one station to the other it will of course be necessary to provide adjustment, as is apparent.

The saw-guides herein illustrated each comprise a base 29, in which is rigidly secured a pair of guide-rods 30, upon each of which guide-rods is mounted one side 31 of a saw-guide cylinder, and each of the sides of the cylinder is provided with a cut-away portion 32 to accommodate the back of a backed saw and is provided with a face 33 to afford a guide for the side of the saw-blade. The two sockets 27 28 are provided so that the guide may

be changed from one position to another to accommodate the work or to accommodate the saw.

The space between the side faces 33 may be regulated by the rotation of the base 29 in its socket, which will move the guide-rods 30 toward or from the plane of the saw-blade, whereby the guide-surfaces will upon the entry of the saw between them be placed nearer or farther apart, as the case may be.

The front of the frame is shown as carrying an apron 34, which is provided at its top with characters 35, indicating the various bevels or angles at which the saw will ordinarily be placed in practice. The lower side of the apron at the front is provided with a sector 36, concentric with the axis of the bushing 17, and which has a plane face 37, which may occupy the plane of the face 38 of the hub or may be in a plane parallel to the plane thereof. At the rearward of the sector 36 is a groove 39, also concentric to said bushing and having a bearing-face 40 on a plane parallel to the plane of the face 37. The beam-arm is provided with a socket 41, in the present instance cylindrical, in which is mounted a clamping member, here shown as a plug 42, having its contour cylindrical and provided at its upper end with a notch or recess 43, making a lip 44, organized to travel in the groove 39. A bearing-face 45 on the lip is organized to bear upon the face 40. The side of the block is cut away at 46 to accommodate an actuator, in the present instance a rock-shaft 47, mounted in a socket 48, transversely disposed in the beam relative to the socket 41. The rock-shaft is shown as having a portion milled out of its center to make a depression 49 and leave a lip 50, organized to bear upon the block to clamp the saw. The bearing-point upon the block may for the purpose of adjustment be movable and is here shown as a screw 51. The lip 50 is shown as cut away at 52, so that its point of action will be brought as near to the center of the rock-shaft as possible. The rock-shaft is provided at its ends with reduced portions 53, which are embraced by split hubs 54, carried by a bow-shaped lever 55, having a finger-piece 56 located adjacent to the handle 26. The split hubs are clamped upon the pins 58 by means of set-screws 57. Pins 58 depend from the beam-arm and pass through openings in the lever 55 and around which pins are shown spiral springs 59 for the purpose of applying tension to the clamping-block. The lower portion of the lever may be bellied out, as at 60, to accommodate the springs. The pins 58 may be provided with heads 61 to assist in assembling the parts. After the most of the parts have been put together the pins, which are shown as screw-threaded, may be passed through the holes in the lever, the springs applied, and the pins screwed into the beam and

then the screw 51 adjusted until the entire force of the spring is brought to bear upon the clamp, as will be indicated by a space being left between the heads 61 of the pins and the face of the lever. The clamp in its clamping action will draw the face 62 on the beam-arm against the face 37 of the sector 36 and will cause friction between the faces 40 and 45, which friction may be modified or removed by moving the lever 55. A small amount of movement will modify the friction, and the limit of movement will permit the friction to become almost negligible, and the spring action may be entirely removed and the friction, if any, the clamp produces will be merely due to gravity and whatever residual magnetism may be in the parts.

To indicate positively to the workman when he has brought the beam-arm to such a position that the guides will compel the saw to cut upon the desired angle, a series of sockets or index notches or recesses 63 may be provided in the face 36, which sockets in the present instance are shown as conical and might be termed "pin" sockets or holes, and the beam-arm as provided with a chamber, in the present instance shown as a socket 64, having a shoulder or ledge 65 at its lower end, in which an indexer 66 may be mounted. The indexer in the present showing is in the form of a pin; but it will be apparent that the indexer may be a bolt of any convenient form, as may also the notches and other parts of the apparatus. This, considered as a whole, is shown as having a body portion 66, a conical pin or bolt 68, organized to mate with the notches or sockets 63, and the stem 69, organized to protrude through the chamber or socket 64 and past the ledge 65, and between such shoulder 65 and the body of the index-pin or bolt may be interposed a suitable coiled spring 70 for throwing the same. The beam-arm is shown as having a socket or chamber 71, transversely disposed to the chamber 64 and in which an actuator 72 for the index-pin may be mounted, and which actuator has in the form illustrated a body portion 73, substantially cylindrical, to guide it in its work, a lever-arm 74, adapted to be engaged by a lug 75 upon the lever 55, and a bearing-face 76, adapted to enter a cut-away opening 77 of the body portion of the pin and to engage an engaging face 78 in such cut-away portion. The actuator may be cut away at 79 to permit it having free action within the pin and to prevent it from engaging it at unintended portions. It also has a head or bead 80 to prevent it from entering the socket too far and jamming the pin. The portion of the indexer adapted for engagement with the notches in the structure herein shown is, as above stated, in the form of a conical pin and located to protrude through the face of the friction-face 62.

The frame, as illustrated, has at its rear a pair of lugs 81, which afford bearing for screws 82, controlling guides or gages 83, having at their forward ends posts 84. Such guides may be shifted back and forth to assist in holding the work, and if it is desired to cut a bevel upon some kinds of work—as, for instance, certain moldings which in practice will be placed in a corner only, resting 10 against the wall at the edges—the molding may be put in a similar position in the box by means of these guides. When the guides are not in use, they may be withdrawn from the front of the back plate and folded down 15 at the rear thereof and “stored” out of the way. The gages are in the present instance adapted to occupy grooves 90 in the floor-board.

In setting the saw at a desired angle it will 20 be necessary merely to press the handle 56 of the lever toward the handle 26 by grasping the same with the thumb and finger, when the clamp will be released from the burden of its spring and the bolt or index-pin will be 25 withdrawn, in which position the arm may be freely shifted to a new position, and when the workman has about reached such position he may permit the lever and handle to separate sufficiently that the lug 75 will not bear 30 upon the lever 74, but will allow the spring 70 to act upon the bolt, when it will run upon the face 87, the clamp in the meantime, however, receiving some of the force of its spring and gripping the clamping-faces slightly. 35 The motion given the beam-arm by the operator may be such that it would carry it past the desired point; but upon the index-pin reaching one of the index-holes it will enter the same and halt the beam, whereupon the 40 clamp will be permitted to have the full force of its spring and securely lock the beam in the position which it has been precisionized to by the index-pin. If, however, the workman desires to use the saw to cut at an angle 45 other than that afforded by the index-pin holes, he may adjust the saw to such position by any means he sees fit and permit the clamp to hold it in such position, the clamp being capable of locking the parts without the intervention of the index-pin.

It will be seen that the board flooring 10 protrudes beyond the edge of the frame slightly and that it is cut away at the edges at 85. (See dotted lines, Fig. 1.) This is to accommodate the saw-guide cylinder when the beam is placed at its extreme position—to wit, the position of cutting an angle of thirty degrees, to do which the front saw-guide will have to be in the socket, as shown at Fig. 3, 55 when it may be shifted along to such position. This is a practical machine, which is capable of cutting upon an angle of thirty degrees from the back face of the frame.

It will frequently happen that the workman 60 will desire to cut a bevel other than on the

angles made standard by the index and may have the line for the cut marked off on the work, in which event he will place the work on the frame and raise the rocker-arm until the spring-catch 86, carried by such arm, is 70 pressed by the muscular expansion of his finger into the notch 87 on the beam, when he can by his hand on the saw swing the same to the desired angle and by raising the rocker-arm slightly release the catch, whereupon the 75 clamp will hold the saw during its cutting.

It will be apparent that at times in practice many details may be changed without departure from the spirit of my invention. Certain of the parts have received especial mention in this regard; but by such reference to such parts it is not meant to exclude or delimit the range of equivalency of the other portions of the structure.

The apron and truss-frame herein shown 85 and described are claimed in my copending application, Serial No. 175,425, filed October 2, 1903, and the feature herein illustrated of the tie-rod or stay connecting the saw-guides and pivoted thereto respectively in the axes of rotation of such saw-guides is claimed in my copending application, Serial No. 175,428, filed October 2, 1903.

Having thus described my invention, I claim—

1. In a miter-box the combination with a frame, of saw-guide-carrying means shiftable thereon; a block to clamp the same together; saw-guides; springs to render the clamp effective; a lever interposed between said block and springs to convey the pressure of the springs to the block and capable upon its actuation of removing the pressure of the springs from the block; a co-operative bolt; and an actuator therefor controlled by said lever; bolt-notches; 100 independent means to impel the bolt into locking engagement therewith to permit its operation to lock to be determined by the presence of an appropriate notch without controlling the operation of the clamp.

2. In a miter-box the combination with a frame embodying work-positioning members, of a beam swiveled thereon; saw-guides carried by the beam; an apron protruding from the frame; a segmental clamping-rail on the 115 apron concentric with the axis of the beam; a guide-surface on the rail; a corresponding guide-surface on the beam; a block mounted on the beam in engagement with said rail and adapted when under pressure to clamp said 120 guide-surfaces together and when free from restraint having no clamping action; a rock-shaft adjacent to said clamping-block and adapted to control the same; a rocker-arm fast on said shaft; a spring to throw said arm 125 and cause said clamp to become active; a series of stop-faces upon said frame; an index-pin carried by the beam to engage therewith; means to throw the pin; and an actuator for the pin located in the path of movement of 130

the rocker-arm at the end of its movement in releasing the clamp.

3. In a miter-box the combination with a frame embodying work-positioning members, of a beam swiveled thereon; saw-guides carried by the beam; an apron protruding from the frame; a segmental clamping-rail on the apron concentric with the axis of the beam; a guide-surface on the rail; a corresponding guide-surface on the beam; a block mounted on the beam in engagement with said rail and adapted when under pressure to clamp said guide-surfaces together and when free from restraint having no clamping action; an adjustable engaging face on the block; a rock-shaft adjacent to said clamping-block and having a lip adapted to bear upon said engaging face and control the block; a rocker-arm fast on said shaft; a spring to throw said arm and cause said clamp to become active; a series of stop-faces upon said frame; an index-pin carried by the beam to engage therewith; means to throw the pin; and an actuator for the pin located in the path of movement of the rocker-arm at the end of its movement in releasing the clamp.

4. In a miter-box the combination with a frame embodying work-positioning members, of a beam swiveled thereon; saw-guides carried by the beam; an apron protruding from the frame; a segmental clamping-rail on the apron concentric with the axis of the beam; a guide-surface on the rail; a corresponding guide-surface on the beam; a block mounted on the beam in engagement with said rail and adapted when under pressure to clamp said guide-surfaces together and when free from restraint having no clamping action; a screw in said block having an engaging face; a rock-shaft adjacent to said clamping-block and having a lip adapted to bear upon said engaging face and control the clamp; a rocker-arm fast on said shaft; a spring to throw said arm and cause said clamp to become active; a series of stop-faces upon said frame; an index-pin carried by the beam to engage therewith; means to throw the pin; and an actuator for the pin located in the path of movement of the rocker-arm at the end of its movement in releasing the clamp.

5. In a miter-box the combination with a frame embodying work-positioning members, of a beam swiveled thereon; saw-guides carried by the beam; a segmental clamping-rail on the frame concentric with the axis of the beam; a guide-surface on the rail; a corresponding guide-surface on the beam; a block mounted on the beam in engagement with the rail and adapted when under pressure to clamp said guide-surfaces together and when free from restraint having no clamping action; an adjustable engaging face on the block; a rock-shaft adjacent to the clamping-block and having a lip adapted to bear upon said engaging face and control the block; a rocker-arm fast

on said shaft; a spring to throw the arm and cause said lip to bear upon the engaging face; an index-scale on the frame; an index carried by the beam to mate therewith; means to advance the index; and an actuator for the index located in the path of movement of the rocker-arm.

6. In a miter-box the combination with a frame embodying work-positioning members, of a beam swiveled thereon; saw-guides carried by the beam; a segmental clamping-rail on the frame concentric with the axis of the beam; a guide-surface on the rail; a corresponding guide-surface on the beam; a block on the beam in engagement with said rail and adapted when under pressure to clamp said guide-surfaces together and when free from restraint having no clamping action; a chamber in the block; a screw entering the chamber and having an engaging face therein; a rock-shaft adjacent to the clamping-block and having a portion adapted to enter the chamber and bear upon said engaging face and control the clamp; a rocker-arm fast on said shaft; a spring to throw said arm and cause the clamp to become active; a series of index-recesses on the frame; an index-pin carried by the beam to mate therewith; means to throw the pin; and an actuator for the pin located in the path of movement of the rocker-arm.

7. In a miter-box the combination with a frame embodying work-positioning members, of a beam swiveled thereon; saw-guides carried by the beam; an apron protruding from the frame; a segmental clamping-rail on the apron concentric with the axis of the beam; a guide-surface on the rail; a corresponding guide-surface on the beam; a block mounted on the beam in engagement with said rail and adapted when under pressure to clamp said guide-surfaces together and when free from restraint having no clamping action; a screw in said block having an engaging face; a rock-shaft adjacent to said clamping-block and having a lip adapted to bear upon said engaging face and control the clamp; a rocker-arm fast on said shaft; and a spring to throw said arm and cause said clamp to become active.

8. In a miter-box the combination with a frame embodying work-positioning members, of a beam swiveled thereon; saw-guides carried by the beam; a segmental guide-surface on the frame; a corresponding guide-surface on the beam; a block mounted on the beam and adapted when under pressure to clamp said guide-surfaces together and when free from restraint having no clamping action; a chamber in the block; a screw entering the chamber and having an engaging face; a rock-shaft adjacent to said clamping-block and having a portion adapted to enter the chamber and bear upon said engaging face and control the clamp; a rocker-arm fast on the shaft; and a spring to throw the arm and cause the clamp to become active.

9. In a miter-box the combination with a frame, of a part movable thereon; saw-guiding means carried thereby; a clamp to control the movement of said part; a spring-pressed lever bearing upon the clamp and so mounted that upon being moved to compress the springs it will relieve the clamp of pressure; an index-pin; and an actuator therefor in the path of movement of the lever during its last stages 5 of compression of the spring.

10. In a miter-box the combination with a frame, of a part movable thereon; saw-guiding means carried thereby; a clamp to control the movement of said part; a spring-pressed lever bearing upon the clamp and so mounted that upon being moved to compress the spring it will relieve the clamp of pressure; means to regulate the pressure of the spring; an index-pin; and an actuator therefor 15 in the path of movement of the lever during its last stages of compression of the spring.

11. In a miter-box the combination with a frame, of a part movable thereon; saw-guiding means carried thereby; a clamp to control the movement of said part; an arm to actuate the clamp; an index-scale; a member to coöperate with the scale as an index when partially retracted and to act therewith as a bolt when released, means to control said 25 member and actuated by said arm; and means to adjust the timing of the actuation of the clamp and the said member one relatively to the other.

12. In a miter-box the combination with a frame, of a beam swiveled thereon; saw-guiding means carried thereby; a guide-surface on the frame; a corresponding guide-surface on the beam; a clamping-rail on the frame; a block mounted in the beam in engagement 35 with said rail and adapted when under pressure to clamp said guide-surfaces together and when free from restraint having no clamping action; a rock-shaft adjacent to said clamping-block and adapted to control the same; a 40 rocker-arm fast on the shaft; a spring to throw the arm and cause the clamp to become active; a series of stop-faces upon the frame; a bolt carried by the beam; means to throw the bolt; and means in the control of the rocker-arm in 45 its movement in releasing the clamp to draw the bolt.

13. In a miter-box the combination with a frame, of a beam swiveled thereon; saw-guiding means carried thereby; an apron protruding 55 from the frame; a segmental clamping-rail on the apron having the axis of the beam for a center; a guide-surface on the rail; a corresponding guide-surface on the beam; a block mounted on the beam in engagement with said rail and adapted when under pressure to clamp said guide-surfaces together and when free from restraint having no clamping action; a rock-shaft adjacent to the clamping-block and adapted to control the same; a 60 rocker-arm fast on said shaft; a spring to

throw the arm and cause the clamp to become active; a series of stop-faces upon the frame; an index-pin carried by the beam; means to throw the pin; and means in the control of the rocker-arm in its movement in releasing the clamp to draw the pin. 70

14. In a miter-box the combination with a frame, of a beam swiveled thereon; saw-guiding means carried thereby; a friction guide-face upon the frame; a corresponding guide-face upon the beam; a block mounted on the beam and adapted when under pressure to clamp said faces together and when free from restraint having no clamping action; a rock-shaft adjacent to said clamping-block and 75 adapted to control the same; a rocker-arm fast on said shaft; a spring to throw said arm and cause said clamp to become active; a series of stop-faces upon the frame; an index-pin carried by the beam; and means in the control of the rocker-arm in its movement in releasing the clamp to draw the pin. 80

15. In a miter-box the combination with a frame, of a beam swiveled thereon; saw-guiding means carried thereby; a friction guide-face upon the frame; a corresponding guide-face upon the beam; a block mounted on the beam and adapted when under pressure to clamp said faces together and when free from restraint having no clamping action; a rock-shaft adjacent to said clamping-block and 90 adapted to control the same; a rocker-arm fast on said shaft; a spring to throw said arm and cause said clamp to become active; a series of stop-faces upon the frame; an index-pin carried by the beam; and means in the control of the rocker-arm in its movement in releasing the clamp to draw the pin. 95

16. In a miter-box the combination with a frame, of a beam swiveled thereon; saw-guiding means carried thereby; a friction guide-face upon the frame; a corresponding guide-face upon the beam; a block mounted in the beam and adapted when under pressure to clamp said faces together and when free from restraint having no clamping action; a rock-shaft adjacent to said clamping-block and adapted to control the same; a rocker-arm fast 100 on said shaft; a spring to throw said arm and cause said clamp to become active; a series of stop-faces upon the frame; an index-pin carried by the beam; means in the control of the rocker-arm in its movement in releasing the clamp to draw the pin; and means to regulate the relative timing of the actuation of the clamping-block and the pin. 105

17. In a miter-box the combination with a frame embodying work-positioning members, of a beam swiveled thereon; saw-guides carried by the beam; a segmental clamping-rail concentric with the axis of the beam; a guide-surface on the rail; a coöoperative guide-surface on the beam; a block mounted on the beam in engagement with said rail and adapted when 110

under pressure to clamp said guide-surfaces together and when free from restraint having no clamping action; a rock-shaft adjacent to the clamping-block and adapted to control the same; a rocker-arm fast on the shaft; and a spring to throw the arm and cause the clamp to become active.

18. In a miter-box the combination with a frame embodying work-positioning members, of a beam swiveled thereon; saw-guides carried by the beam; a segmental clamping-rail concentric with the axis of the beam; a guide-surface on the rail on the plane of movement of the beam when swinging on its swivel; a co-operative guide-surface on the beam in contact therewith; a second guide-surface on the rail in a plane parallel to said first guide-surface; a block mounted on the beam in engagement with said second guide-surface upon the rail and adapted when under pressure to clamp said first guide-surface and the guide-surface on the beam together and when free from restraint having no clamping action; a rock-shaft adjacent to the clamping-block and adapted to control the same; a rocker-arm fast on the shaft; and a spring to throw the arm and cause the clamp to become active.

19. The combination with a miter-box having work-positioning members, of saw-guides carried by a frame and swiveled thereto; a segmental clamping-rail on the box concentric with the axis of the frame; a guide-surface on the rail; a corresponding guide-surface on the frame; a block mounted on the frame in engagement with the rail and adapted when under pressure to clamp the guide-surfaces together and when free from restraint having no clamping action; a rock-shaft adapted to control the clamping-block; a rocker-arm fast on the rock-shaft; a spring to throw the arm and cause the clamp to become active; a series of index-pin holes upon the box; an index-pin carried by the frame; means to throw the pin; and an actuator for the pin having an arm in the path of movement of the rocker-arm at the end of its clamp-releasing movement.

20. The combination with a beam-arm, of a frame carrying the same; saw-guides on the beam; a clamping-block to hold the beam in its adjusted position; means to actuate the clamp and comprising a rock-shaft; a rocker-arm; springs bearing on the rocker-arm to force the rock-shaft upon the clamping-block; and pins to guide the rocker-arm and having heads in the direction of the spring-pressed movement of the same but beyond the limit of the same when adjusted.

21. The combination with a swiveled member, of a frame carrying the same, saw-guides mounted on said member; a clamping-plug to hold the beam in its adjusted position; an adjustable bearing-face on the plug; means to actuate the clamping-plug and comprising a rock-shaft having an engaging face to bear upon said adjustable bearing-face, a rocker-

arm, springs bearing on the rocker-arm to force the rock-shaft to its work, and pins to guide the rocker-arm and having heads in the direction of the spring-pressed movement of the same but beyond its limit of movement when adjusted.

22. The combination with a beam-arm, of a frame carrying the same; saw-guides mounted on the beam; a clamping-block to hold the beam in its adjusted position; and means to actuate the clamping-block and comprising a rock-shaft, a rocker-arm, pins to guide the rocker-arm, and having stop-heads for the same, springs surrounding the pins and forcing the rock-shaft upon the clamping-block, and an adjustable bearing-face in the clamping-block, whereby the rocker-arm may be caused to apply the entire force of the springs upon the clamping-block and to clear the stop-heads.

23. The combination with a beam-arm, of a frame carrying the same; a guide-face upon the frame engaging a face on the beam-arm; a clamp bearing-face upon the frame; saw-guides mounted upon the beam-arm; a clamping-block reciprocatable upon said beam-arm and having a lip to engage said bearing-face to hold the respective guide-faces together; a rocker-arm adapted to actuate said block; spring-pressed means to control said rocker-arm, and means to guide the same.

24. The combination with a miter-box, of saw-guides; a beam swiveled to the box and carrying the guides; locking mechanism on the beam; a rocker-arm to actuate the same; an engaging face on the beam; and a spring-catch on the rocker-arm so positioned that pressure from the muscular expansion of the finger of the operator will press the spring-catch into the engaging face on the beam, and a slight lift on the lever will release the same.

25. The combination with a miter-box having work-positioning members, of saw-guides carried by a frame swiveled thereto; a clamp mounted on the frame and organized when under pressure to clamp the frame and box together and when free from restraint having no clamping action; a rock-shaft organized to control the clamp; a rocker-arm fast on the rock-shaft; a spring to throw the arm and cause the clamp to become active; a series of index-pin holes upon the box; an index-pin carried by the frame; means to throw the pin; and an actuator for the pin having an arm in the path of movement of the rocker-arm at the end of its clamp-releasing movement.

26. The combination with a miter-box having work-positioning members, of saw-guides; a beam-arm swiveled to the box and carrying the guides; a clamp mounted on the beam-arm and adapted when under pressure to clamp the beam-arm and box together and when free from restraint having no clamping action; a rocker-arm to control the clamp; a series of

index-pin holes upon the box; an index-pin carried by the beam-arm; means to throw the pin; and an actuator for the pin having an arm in the path of movement of the rocker-arm.

27. In a miter-box the combination with a frame embodying work-positioning members, of a beam swiveled thereon; saw-guides carried by the beam; a guide-surface on the frame, a mating guide-surface on the beam; a block mounted on the beam and organized when under pressure to clamp said guide-surfaces together and when free from restraint having no clamping action; a chamber in the block; a screw entering the chamber and having an engaging face; a rock-shaft adjacent to said clamping-block and having a portion adapted to enter the chamber and bear upon said engaging face and control the clamp; a rocker-arm fast on the shaft; a spring to throw the arm and cause the clamp to become active; index-points on the frame; an index-pin carried by the beam; a chamber in the pin; a bearing-face therein; a rock-shaft adjacent to the pin and having a portion adapted to enter the chamber and bear upon said engaging face; and an arm on said shaft in the control of the rocker-arm.

28. In a miter-box the combination with a frame embodying work-positioning members, of a beam swiveled thereon; saw-guides carried by the beam; a guide-surface on the frame; a mating guide-surface on the beam; a block mounted on the beam and adapted when under pressure to clamp said guide-surfaces together and when free from restraint having no clamping action; a chamber in the block; an adjustable engaging face in the chamber; a rock-shaft adjacent to said clamping-block and having a portion adapted to enter the chamber and bear upon said engaging face and control the clamp; a rocker-arm fast on the shaft; means to throw the arm and cause the clamp to become active; index-points on the frame; an index-pin carried by the beam; means to throw the pin; a chamber in the pin; a bearing-face therein; a rock-shaft adjacent to the pin and having a portion adapted to enter the chamber and bear upon said engaging face; and an arm on said shaft in the control of the rocker-arm.

29. In combination with a miter-box, a beam-arm pivotally mounted thereon, a series of recesses in the box adjacent to the path of movement of said beam-arm, a pin carried by the beam-arm and adapted to coöperate with said sockets, an operating-lever pivoted to said beam-arm, means of connection between the operating-lever and the pin, the organization being such that the operating-lever may have a swinging movement and the pin a reciprocating movement, and means controlled by the operating-lever to normally maintain the beam-arm in place relatively to the box.

30. In combination with a miter-box, a beam-arm pivoted thereto, saw-guides carried by the beam-arm, an operating-lever pivoted to said beam-arm, a locking-pin having a working fit in a guideway in said beam-arm, a series of sockets in the miter-box adapted to coöperate with said pin, means to connect said operating-lever and said pin and permit the former to oscillate upon its pivot, and the latter to reciprocate in its guideway, further means controlled by said lever to hold the beam-arm in place relatively to the miter-box, and means to lock said operating-lever and maintain the pin out of engagement with the sockets.

31. In a miter-box, the combination with a work-table having a segmental face, a beam-arm pivoted concentrically thereto and having a pin-guideway in the region of said face and constituting a comparatively long bearing for a pin, a pin mounted and having a close working fit in the said guideway and having an actuator-engaging face at a point midward of the limits of its engagement with the guideway; a series of recesses in said segmental face to accommodate said pin, yieldable means to impel said pin toward said face and into the recesses, a lever carried by the beam-arm and having a swinging motion, and an actuator to engage said face on the pin and controlled by the said lever, the lever controlling other means and arranged for play in so controlling independent of the operation of the actuator, whereby the pin may be reciprocated in substantially a straight line upon the swinging of the lever.

32. In a miter-box, the combination with a work-table having a segmental face, a beam-arm pivoted concentrically thereto and having a pin-guideway in the region of said face, a pin in said guideway, a series of sockets in said face to accommodate said pin, yieldable means to impel said pin toward said face and into the sockets, a lever carried by the beam-arm and having a swinging motion, means of connection between the lever and the pin to reciprocate the pin upon the swinging of the lever, and a digitally-controlled spring-catch carried by said lever to lock the lever, a catch-face on the beam adapted to receive the catch when the lever nearly reaches its limit of movement, and hold the pin in an inactive position, and upon the shifting of the lever to its limit of movement to release said catch.

33. In a miter-box, the combination with a work-table; of a beam-arm pivoted thereto; saw-guides rotarily mounted on said beam-arm; a step or station at one end of the beam-arm for one of said guides; a plurality of steps or stations at the other end of said beam-arm for another of said guides; a support to connect the guide at one station to the guide at the other station; and means to permit the adjustment of the support upon changing the movable guide from one step or station to

another step or station and to permit the rotation of said guides.

34. In a miter-box the combination with a frame, of a part movable thereon; saw-guiding means carried thereby; a clamp to control the movement of said part; an arm to actuate the clamp; an index-scale; a member to coöperate with the scale as an indexer when partially retracted and to act therewith as a bolt when released, and means to control said member and actuated by said arm.

35. In a miter-box, the combination with a frame to position the work, of saw-guides; a beam pivoted to the frame and carrying the saw-guides; a pin to lock the beam in various

positions of adjustment relative to the positioning means; means to throw the pin; a clamp to coöperate with the pin in holding the beam at its adjusted position; and means to draw the pin, relax the clamp, and hold the clamp in partial relaxation after the pin has been released to the influence of its holding means.

Signed at Nos. 9 to 15 Murray street, New York, N. Y., this 19th day of September, 1903. 25

FRANCIS H. RICHARDS.
